UNITED STATES PATENT OFFICE.

CHARLES N. CORYELL, OF MAMARONECK, NEW YORK, ASSIGNOR TO SCOVILL MANUFACTURING COMPANY, OF WATERBURY, CONNECTICUT, A CORPORATION OF CONNECTICUT.

VANITY CASE.

Application filed March 3, 1925. Serial No. 12,825.

This invention relates particularly to vanity cases of the double compact type, carrying for instance, both the face powder and the rouge with puffs and other accessories.

The objects of the invention are to provide a complete case of this nature, which will be of small, compact, attractive form, of practical, relatively inexpensive construction and which will be convenient and handy for use.

In the drawings accompanying and forming part of this specification, one of the practical, commercial embodiments of the invention has been illustrated, but it is to be understood that the structure may be modified and changed in various ways without departure from the broad spirit and scope of the invention.

20 Figure 1 is a sectional view showing the case open at both sides.

Figure 2 is a top plan view of the same.

15 Figure 3 is a sectional plan view of one of the covers as on substantially the plane of line 3—3 of Figure 1.

Figure 4 is a perspective view of one of the bezels for holding the mirrors in place.

25 Figure 5 is an enlarged broken cross sectional view of the same as on line 5—5 of Figure 4.

Figure 6 is a plan view of one of the covers.

Figures 7 and 8 are sectional details as on lines 7—7, 8—8 of Figure 6.

30 Figure 9 is a perspective view of the intermediate holder for the compacts.

Figures 10 and 11 are enlarged sectional details on lines 10—10 and 11—11 of Figure 9.

40 Figure 12 is an edge view of the case in closed condition.

The covers 14, 15, are shown as of similar construction, each consisting of a shallow, saucer-like shell having an inturned flange 16 about the rim of the same, interrupted at one point, 17, for the hinge connection and provided at a substantially diametrically opposite point with an integral lip 18 partially severed and bent out from the flange.

Within the covers are the mirrors 19, 20, held by cupped bezels 21 of like construction, sprung beneath the flanges 16 so as to directly overlie the mirrors, said bezels each

having a recess 22 at one edge for the hinge 65 and an inwardly pressed lug 23 forming one element of a clasp for holding the case closed.

The intermediate compact carrying section is shown as made up of two dished ring like members 24, 25, substantial counterparts of one another except that one, 24, has a confining bead 26, Figure 10, turned over the rim of the other to secure the two together. These members are shown formed with hinge loops 27 of a length to fit in the gaps 17 in the flanges 16 of the covers. Hinge wires 28 extended through these loops and engaged beneath the flanges 16, as indicated in Figure 3, serve to hingedly unite 70 the covers to the intermediate section. To receive these hinge wires, the covers are shown formed with beads 28', providing cavities or seats 29 beneath the flanges and behind the bezels 21. This construction 75 provides simple, concealed hinges for both covers, which are easily assembled and which cannot become accidentally disengaged.

At points opposite the hinge loops, the 80 intermediate members are shown provided with lugs 30 cut from the sides of the same at 31 and bent outward into position for snapping engagement with the retaining lugs 23 on the bezels. Each cover is thereby releasably held closed against the intermediate or body member.

In the present disclosure, the body member is employed as a holder for a rouge compact and a powder compact and the puffs 85 which are used with the same. The rouge compact is shown carried in a shallow tray 32 and the powder compact in a deeper tray 33, said trays being of the same diameter and so interchangeably engageable in the 90 equal size seats or openings 34 provided in the two body members. These trays may be held in place by simply forcing them into these seats in back to back relation, as shown in Figure 1, and the puffs 35, 36, are preferably made of a size to be frictionally held 100 in the two trays over the compact material.

The bead 26, securing the two body members together reinforces the entire structure, serves as a stop for the two covers, as indicated in Figure 12, and further, adds to the general ornamental appearance of the device, this intermediate bead in combina-

- tion with the beads on the covers presenting a balanced symmetrical effect. The center bead may project slightly as indicated so as to act as a protecting rim, preventing injury to the covers if the case is dropped. This center bead also serves as an abutment in opposition to the projecting finger lugs on the covers for gripping by the fingers when opening said covers.
- 10 The seats for the cosmetic trays provide an opening extending entirely through the intermediate body or holder so that if one tray should stick, it may be forced out from the inside after first removing the other tray.
- What is claimed is:
1. A vanity case comprising a two-part body member, each part having a dish shaped portion and a rim forming an annular channel therebetween, one of said parts having a bead secured to its rim and engaged over the rim of the other part, each part having a strip struck out across said channel joining said dish shaped portion and rim to form a hinge loop, and cover sections cooperating with said loops.
  2. A vanity case comprising a body member having hinge loops in the edge portion of the same, covers at opposite sides of the body member having folded edges forming flanges recessed to receive said loops, hinge wires extended through the loops and engaged beneath the flanges of said covers and bezels engaged in the covers beneath the flanges and covering the hinge wires.
  3. A vanity case comprising a body member having hinge loops in the edge portion of the same, covers at opposite sides of the body member having folded edges forming flanges recessed to receive said loops, annular hinge wires extended through the loops and engaged beneath the flanges of said covers and bezels engaged in the covers beneath the flanges and covering the hinge wires, the covers having beads beneath the flanges and behind the bezels forming annular seats for the hinge wires.
  4. A vanity case comprising an intermediate holder and covers hinged to opposite sides of the same, said covers having beaded edges and the holder having a beaded edge intermediate and adjoining said first beaded edges when said case is in closed position.
  5. A vanity case comprising an intermediate holder and covers hinged to opposite sides of the same, said covers having beaded edges and the holder having a beaded edge intermediate and adjoining the beaded edges of the covers, clasps for the two covers and finger holds on said covers adjoining the intermediate bead for facilitating the separate opening of the respective covers.
  6. A vanity case comprising a body member having hinge loops in the edge portion
  7. A vanity case comprising cupped members, one provided with a flange engaged over the rim of the other, said members having seats for cosmetic holders and covers hingedly connected to the respective members.
  8. A vanity case comprising cupped members, one provided with a flange engaged over the rim of the other, said members having seats for cosmetic holders and covers over the respective members, each of said members having a clasp element and the covers having co-acting clasp elements operating therewith.
  9. A vanity case comprising dished members secured in face to face relation and having openings providing seats for cosmetic holders, said dished members having hinge loops in edge portions of the same and outstruck lugs substantially opposite said hinge loops, covers held by said hinge loops and catches on the covers for engagement by the outstruck lugs.
  10. A vanity case comprising a body member, a cover hinged thereto, an article in said cover, a bezel ring engaged in said cover to hold said article in place, and cooperating catches on said body member and on said bezel ring to hold said cover shut.
  11. A vanity case comprising a body member having hinge loops on opposite sides of the same, covers for engagement over opposite sides of said body member having edge flanges interrupted to receive the hinge loops and hinge wires extending through said loops and spring beneath the edge flanges of the covers.
  12. A vanity case comprising a body member having hinge loops on opposite sides of the same, covers for engagement over opposite sides of said body member having edge flanges interrupted to receive the hinge loops, hinge wires extending through said loops and sprung beneath the edge flanges of the covers and bezels engaged in the covers over said hinge wires.
  13. A vanity case comprising a two-part body member, one part having a rim, the other part having a bead, said parts being held together by the bead on one part engaged over the rim of the other part, said two parts having openings therein, cosmetic trays seated in said openings, hinge loops on

- said body parts, covers having edge flanges interrupted to take such hinge loops, hinge wires extending through said loops and engaged beneath said flanges, bezels seated in the covers beneath the flanges and separate catches for the two covers.
14. A vanity case comprising a two-part body member, one part having a rim, the other part having a bead, said parts being held together by the bead on one part engaged over the rim of the other part, said two parts having openings therein, cosmetic trays seated in said openings, hinge loops on said body parts, covers having edge flanges interrupted to take such hinge loops, hinge wires extending through said loops and engaged beneath said flanges, bezels seated in the covers beneath the flanges and separate catches for the two covers consisting of lugs on the body parts and cooperating lugs on the bezels.
15. A vanity case comprising a two-part body member, one part having a rim, the other part having a bead, said parts being held together by a bead on one part engaged over the rim of the other part, said two parts having openings therein, cosmetic trays seated in said openings, hinge loops on said body parts, covers having edge flanges interrupted to take such hinge loops, hinge wires extending through said loops and engaged beneath said flanges, bezels seated in the covers beneath the flanges and separate catches for the two covers and lugs turned out of the edge flanges of the covers to provide finger holds for releasing the catches.
16. A vanity case comprising a body member provided with a hinge loop, a cover member having an inturned flange at the edge of the same interrupted to receive the hinge loop, an article holding bezel seated in the cover beneath the flange and recessed at one edge for the hinge loop and a hinge wire extending through the loop beneath the cover flange and behind the bezel.
17. A vanity case comprising a body member provided with a hinge loop, a cover member having an inturned flange at the edge of the same interrupted to receive the hinge loop, an article holding bezel seated in the cover beneath the flange and recessed at one edge for the hinge loop, a hinge wire extending through the loop beneath the cover flange and behind the bezel, a catch lug on the bezel at a point substantially opposite the recess therein and a cooperating catch on the body member.
18. A vanity case comprising an intermediate holder and covers at the opposite sides of the same, said covers having beaded edges and the holder having an intermediate bead projecting beyond and adjoining the cover beads.
19. A vanity case comprising an intermediate holder and covers at the opposite sides of the same, said covers having beaded edges and the holder having an intermediate bead projecting beyond the cover beads and lips projecting beyond the beads of the covers in opposition to the projecting intermediate bead for facilitating opening of the two covers.
20. A vanity case comprising a holder having an opening extending entirely therethrough, cosmetic trays seated in the opposite ends of said opening, the sides of said trays having projections thereon to limit the position of said trays in said opening, each tray being removable out of its respective end.
21. A vanity case comprising a body member having a body portion and a rim forming an outer annular channel therebetween, said member having a strip struck out across said channel to form a hinge loop, a co-operating section having a pintle disposed under said loop to hingedly connect said member and section.
22. A vanity case comprising a body member, a cover member having an annular in-turned flange, means for hingedly connecting said members together including a hinge wire seated in the cover member under said flange, and a bezel seated over said hinge wire and beneath said flange.
23. A vanity case comprising a body member having a body portion and a rim forming an outer annular channel between said portion and rim, said member having a strip struck out across said channel to form a hinge loop, and a co-operating section having a hinge pintle disposed under said loop and a rim disposable in said channel.
- In testimony whereof I have hereunto set my hand.
- CHARLES N. CORYELL.
